UNITED STATES PATENT OFFICE.

HATTIE C. JENSEN, OF SALT LAKE CITY, UTAH.

DESIGN FOR A SUIT OF PLAYING-CARDS.

44,004.

Specification for Design.

Patented May 13, 1913.

Application filed July 13, 1912. Serial No. 709,298. Term of patent 3½ years.

To all whom it may concern:

Be it known that I, HATTIE C. JENSEN, a citizen of the United States, and resident of Salt Lake City, in the county of Salt Lake and State of Utah, have invented a new, original, and ornamental Design for a Suit of Playing-Cards, of which the following is a specification, reference being had to the accompanying drawings, forming part thereof.

The drawing is a plan view of certain playing cards showing my design.

I claim:

The ornamental design for a suit of playing cards as shown.

HATTIE C. JENSEN.
